FLAG CONTAINER AND ATTACHING MEANS

John R. S. Crowder, Chicago, Ill., assignor to
Martha H. Crowder, Chicago, Ill.

Application August 27, 1956, Serial No. 606,503

6 Claims. (Cl. 116—173)

This invention relates to a flag container and attaching means.

Advertising and publicity campaigns, and particularly political campaigns, frequently involved the use of flags having the desired emotional, inspirational or other indicia imprinted thereon. In order to assure wide distribution and use of these flags, it is desirable that they be readily attachable to some existing flagstaff member such, for example, as is provided by the tubular radial antenna with which most automotive vehicles are provided. It is further desirable that such flags be inexpensive but at the same time constructed of a durable material so that they will not become frayed or worn during the period of intended use.

It is further desirable that means be provided for readily attaching such flags to existing flagstaffs. Heretofore, an undesirable item of expense in the merchandising and distribution of such flags has resided in the cost of containers for the flags and attaching means. The instant flag as sold is accompanied by an attaching means. It is usually necessary or desirable that they be packed in some box or container and it frequently happens that the cost of the box or container approximates the total cost of the flag and attaching means.

It is an object, therefore, of this invention to provide a flag attaching means which, at the same time, provides a satisfactory and attractive container in which the flag may be distributed and sold or in which the flag may be stored when not in use.

According to the present invention, this desired result is accomplished by providing a tubular casing of resilient material which is open at each end and which is provided with a longitudinal opening along one side to which the rolled flag may be inserted. One side of the tubular casing is preferably flattened somewhat to afford a surface on which may be imprinted any desirable data such, for example, as the name and address of the manufacturer, the trade mark by which the product is designated or the like. When it is desired to attach the flag to a flagstaff, it is only necessary that the same be removed from the casing through the longitudinal side opening, an edge of the flag wound about the flagstaff, and the casing engaged thereover to resiliently grip the edge of the flag between its inner surface and the outer surface of the flagstaff.

It is accordingly an important object of the present invention to provide a flag container and attaching means of simple and inexpensive construction which may be used as a merchandising package, a storage package for the rolled flag and which, at the same time, serves as a convenient and effective attaching means for securing the flag to a flagstaff.

Other and further important objects of the present invention will be apparent from the disclosures in the following specification and the accompanying drawings.

On the drawings:

Figure 1 is a side elevation view of the flag attaching means of this invention in association with the flagstaff

2

member, such as a radio antenna holding the flag in display position thereon;

Figure 2 is a side elevation view of the flag container and attaching means of this invention showing the rolled flag positioned within the tubular casing which forms both the container and the attaching means;

Figure 3 is a section on the line III—III of Figure 2;

Figure 4 is an elevation view showing a side of the container opposite to the longitudinal opening therein;

Figure 5 is a section on the line V—V of Figure 1.

As shown on the drawings:

The tubular casing which forms the combined container and flag attaching means of this invention is generally designated by the reference numeral 10 and is preferably made of extruded plastic-resin material such, for example, as cellulose acetate, although it may be formed of any resilient sheet-like material.

The tubular casing has a somewhat flattened portion 10a, reentrant portions 10b and outwardly flaring edge portions 10c which decline in longitudinal opening extending along the entire length of one side of the casing. The casing is open at both ends.

A flag 11, preferably but not necessarily, made of plastic impregnated cloth and imprinted with suitable indicia 12 may be rolled up and carried within the casing as shown in Figure 3 or carried for display on a tubular flagstaff member 13 which, for exemplary purposes, is shown in Figure 1 as a tubular radio antenna of an automotive vehicle.

Figure 5 illustrates the manner in which the flag 11 is secured along one edge to the tubular flagstaff member 13. As shown in Figure 5, an end portion 11a of the flag 11 is wound about the tubular member 13 after which the casing 10 is engaged thereover so that the inner surface of the flat portion of the casing 10 in the re-entrant portions 10b of that casing grip said portion 11a of the flag firmly to the outer surface of the tubular flagstaff member 13.

The flattened portion 10a of the casing affords a desirable surface on which may be imprinted identifying indicia such as the name of the manufacturer, a desired trademark or any other desired decorative or identifying indicia. The manner in which such indicia may be imprinted on said surface 10a is indicated by the reference numeral 14 and I have found that such indicia readily may be imprinted on the casing by a simple roll printing operation.

By using a polyvinyl resin impregnated cloth as a material for the flag 11, the flag is given a certain stiffness which holds it in display position and, at the same time, it retains sufficient flexibility so that it may be rolled and re-rolled for storage within the casing 10 without destroying or impairing the attractiveness of the indicia imprinted thereon. Furthermore, such impregnation renders the flag weather-resistant.

It will be apparent from the foregoing description that I have provided a flag container and attaching means which is simple and inexpensive, serving the combined functions of providing a container in which the flag may be carried in rolled position for sale, distribution or storage, such container at the same time providing a convenient and efficient means for attaching the unrolled flag to a flagstaff by resilient gripping of an edge of the flag between the flagstaff and said container.

The provision of the surface 10a on which identifying or other indicia may be imprinted adds to the salability of the device.

I am aware that details of construction may be varied without departing from the principles of this invention and I therefore do not propose limiting the patent granted hereon otherwise than necessitated by the prior art.

I claim as my invention:

1. In combination, an elongated open-end tubular casing of resilient material having a curved side portion, a pair of longitudinal edge portions connected to the side portion and defining a longitudinal opening extending along the entire length of the casing and parallel to the longitudinal axis of said side portion, re-entrant portions extending along each edge portion of the casing parallel to the opening therein to add resiliency to the casing in a transverse plane and rigidity to the casing in a longitudinal plane thereof, a flagstaff member and a flag wound thereabout having an end portion, the re-entrant portions and said side portion of the casing resiliently clamping said end portion of the flag to said flagstaff leaving said edge portions of the casing extending outwardly and away from the clamped portion of the flag to provide longitudinal surface portions guarding the flag from injury during movement thereof around said flagstaff member.

2. A flag container, comprising a flag and an open-ended casing therefor having a side portion and opposed spaced and generally V-shaped edge portions defining a longitudinal opening extending parallel to the longitudinal axis of the side portion, the vertices of the V-shaped edge portion resiliently bearing against the flag and maintaining said flag against the inner surface of the side portion.

3. In a package combination, an elongated open-end tubular casing of resilient material having sides and a longitudinal opening along the entire length and parallel to the axis thereof, a generally flat portion opposite said opening, generally V-shaped re-entrant portions extending along each side of the casing parallel to the opening therein to add resiliency to the casing in a transverse plane and rigidity to the casing in a longitudinal plane thereof, and a rolled flag insertible through said longitudinal opening and resiliently held within said casing to prevent the rolled flag from being folded transversely of its longitudinal axis.

4. In combination, an elongated open-end tubular casing of resilient material having sides and a longitudinal opening along the entire length and parallel to the axis thereof, re-entrant portions along each side of the casing parallel to the opening therein to add resiliency to the casing transversely thereof and rigidity to the casing longitudinally thereof, a flagstaff member resiliently engaged by said casing, and a flag having an end portion engaged

around said flagstaff member gripped to the outer surface of said flagstaff member by the re-entrant portions of said casing whereby the gripped portion of the flag is held substantially rigid while its opposite end is free to flap.

5. In combination, an elongated open-end and open
sided C-shaped tubular casing of resilient material having
a longitudinal opening along the entire length and parallel
to the axis thereof, slightly flattened portion on
10 that side of the casing opposite said opening to provide
an advertising surface thereon, re-entrant portions of
V-shaped configuration along each side of the casing parallel
to the opening therein to add resiliency to the
casing transversely and rigidity to the casing longitudinally
15 thereof, flat longitudinal surface portions extending along
said opening, and a rolled flag insertible through
said longitudinal opening and resiliently held within
said casing, whereby the rolled flag can not be
folded transversely of its longitudinal axis.

20 6. A package for ready-to-use foldable flag comprising
a rolled flag and an elongated open-end tubular casing
of resilient material having a longitudinal opening along
the entire length and parallel to the axis thereof, said
tubular casing being slightly flattened on its closed side
25 opposite said opening, said tubular casing having re-en-
trant portions extending longitudinally along and adja-
cent the edge portion thereof to add resiliency to the
casing transversely thereof and substantial rigidity to the
casing longitudinally thereof, said rolled flag insertible
30 through said longitudinal opening and resiliently held
therein against longitudinal folding thereof, whereby the
rolled flag may be removed from the casing and have
one end thereof assembled about a flagstaff member, and
said flag resiliently clamped to said flagstaff member by
35 said tubular casing when the casing is placed about said
end of the flag with said end interposed between said flag-
staff member and the interior clamping portions of said
casing.
